UNITED STATES PATENT OFFICE.

JOSEPH E. BOHNER, OF ANSONIA, CONNECTICUT.

DESIGN FOR A LAMP-FOUNT HOLDER.

SPECIFICATION forming part of Design No. 24,436, dated June 25, 1895.

Application filed May 11, 1895. Serial No. 549,011. Term of patent 3½ years.

To all whom it may concern:

Be it known that I, JOSEPH E. BOHNER, a citizen of the United States, residing at Ansonia, in the county of New Haven and State of Connecticut, have invented and produced a new and useful Design for Lamp-Fount Holders, of which the following is a full and complete specification, reference being had to the accompanying drawings, which illustrate the design.

In the drawings, Figure 1 represents the side view of a lamp-fount holder, illustrating my design; and Fig. 2 represents the same at right angles to the position indicated in Fig. 1.

15 The design consists of a lamp fount holder

of the general outline form illustrated, the letter A indicating Napoleonic medallions; B indicating intermediately arranged helmets and arms, with flambeaux C between the medallions and helmets. Other accessory de- 20 signs and figures are added as shown.

The essential features of the design are those particularly above referred to.

What is claimed as new is—

The design for lamp founts and similar articles, substantially as shown and described.

JOSEPH E. BOHNER.
